UNITED STATES PATENT OFFICE.

CHARLES TWEEDIE, OF JEFFERSON CITY, MISSOURI.

BOOT AND SHOE.

1,115,038.

Specification of Letters Patent. Patented Oct. 27, 1914.

Application filed August 27, 1913. Serial No. 786,847.

To all whom it may concern:

Be it known that I, CHARLES TWEEDIE, a citizen of the United States, and a resident of Jefferson City, in the county of Cole and State of Missouri, have invented a new and useful Improvement in Boots and Shoes, of which the following description, with the accompanying drawings, is a specification.

My invention relates to an improved shoe bottom consisting of a short sole and heel.

The invention comprises a combination heel-seat and heel as an article of manufacture, and is intended both to improve boots and shoes, and to cheapen the manufacture thereof by economizing in labor and material.

Further objects of the invention appear in connection with the following description thereof, reference being had to the accompanying drawings, and in what the invention consists is particularly defined in the appended claims.

In the drawings, in which like characters designate the same parts in the several views,—Figure 1 is an isometric view of a shoe after lasting and sewing on a short outsole, beveled ready for the application of my improved combined heel seat and heel. Fig. 2 is a bottom plan view of a shoe with short outsole and heel attached, showing nails applied with regular heel railing machine, for securing the heel to the shoe; and Fig. 3 is a vertical cross-section taken lengthwise of a finished shoe, showing the means for attaching the heel piece to the short sole, counter, upper and insole. Fig. 4 is an isometric bottom plan of a partly finished short outsole, showing the scarf or bevel at the heel end thereof where the grain side of the leather has been skived off; Fig. 5 is an edge view of the same; Fig. 6 is an isometric bottom plan of the bottom lift, or layer, of my improved heel, which forms a continuation of the short sole, corresponding to what is commonly known as the heel seat of an outersole; Fig. 7 is an edge view of the same; Fig. 8 is an isometric view of my improved heel, which is the combination of a regular heel with my heel seat; Fig. 9 is a top plan of the side jaws of a heel compressing mold. Fig. 10 is an isometric side view of my improved top former for a heel compressing mold.

In manufacturing my improved combination shoe sole and heel I first block out a blank piece for the short sole. The forepart 22 of the short sole is rounded out from the

blank to conform to the style wanted, and the shank end 23 is beveled off on the wearing, or grain side. The short sole 24, thus formed, may be channeled, molded and otherwise stock fitted in the same manner as is practised in modern shoe factories.

In building my improved heel, the same method of construction is employed as that now employed in modern heel factories, except that my heel is one heavy lift or layer higher than the ordinary heel, caused by the addition to it of the heel seat portion 25 of the sole. The breast end 26 of the heel seat portion or lift 25 is scarfed on the lower edge. (See Figs. 6 and 7.) The heel 27 is built up and compressed and molded in any heavy pressure heel molding-compressing machine in general use, using the regular side jaws 34 with my improved top mold 35 (see Figs. 9 and 10).

After the shoe is lasted in the regular way, the short sole 24 is attached to and fastened to the insole 28, counter 29, and upper 30, by tacking and sewing or nailing in the regular way. The scarfed shank end 23 of the sole may or may not be nailed down, as it will be securely fastened by the heelng machine operation. The shoe sole is then "leveled" in the usual manner, but the usual succeeding long sole operations of loose nailing the heel seat and rough trimming the projection of the heel seat portion of the sole are both eliminated by my invention. In my process, the next operation after leveling is the nailing on of the heel piece 27 by the regular heel nailing or attaching machine, except that the nails 32 are driven through the insole and clenched instead of terminating in the insole. The top lift 33 of the heel is spanked on in this heel nailing operation. The heel piece 27 can be adjusted either sidewise or lengthwise independently of the sole, thereby enabling the usual rough trimming of the heel seat to be dispensed with, as the final heel trimming suffices for finishing the heel and seat to the proper contour. The joint between the scarfed ends of the short sole and heel seat lift 25 of the heel is covered by the projecting breast portion 31 of the heel, thereby protecting it from moisture.

By reason of my improved construction and method, many advantages are obtained. First, in the use of the short sole there is a saving of twenty per cent., more or less, of the most expensive and durable portion of a

sole leather hide, or of any material suitable for sole purposes.

While I do not claim the short sole as a new discovery, I do know that is not in common use; which is an evidence that no practical results have been obtained heretofore by any manufacturing method of short sole construction heretofore adopted or invented. My invention, however, makes it possible not only to use the short sole successfully and economically, but permits of a still greater saving by way of my improved heel, which can be constructed throughout (including the heel seat piece, or extra bottom lift or layer of heel) of inferior leather or substitutes for leather. Furthermore, my invention eliminates the operations of cementing, gluing or tacking on of heel end pieces in the first stages of manufacture; also the operations of the heel seat nailing machine (loose nailing) with the expensive nails required in said operation; also the operation of rough trimming the heel seat of sole with the heel seat trimming machine. It will be readily seen, therefore, that there is not only a great saving in the various articles or materials of manufacture by my invention, but there follows also a saving in the cost of labor in the elimination of the aforesaid operations.

Having thus described and explained my invention, what I claim and desire to secure by Letters Patent is,—

1. A heel for boots and shoes comprising a plurality of lifts secured together, the bottom lift being shorter than the others at its inner end, said inner end being beveled on its outer face.

2. A shoe comprising a short sole of sole leather having its shank end beveled on the grain side, and a heel secured to said short sole and having a heel seat portion forming an extension of said short sole, said heel seat portion being shorter than said heel and having its inner end beveled on the outer side to lap the beveled end of said short sole.

3. A shoe having a sole comprising a front portion of sole leather or other suitable

sole material with its shank end skived to a bevel on the grain or wearing surface of said sole, and a heel having a bottom lift or layer of either inferior leather or a substitute for leather, said lift being shorter than the adjoining lift or layer and with its short end 55 toward the breast or straight end of said heel, said short end of said heel lift being skived to a bevel, the extension thus left between the beveled end of said short lift or layer and the breast line of said heel forming a suitable and substantial lap and union of both the forepart of said sole and said heel when attached to the bottom of a shoe by the heelng machine process, substantially as described. 65

4. In combination in a shoe, a built up bottom comprising a front portion of sole leather or other suitable sole material with its shank end skived to a bevel on the grain or wearing surface of said sole, and a heel 70 having a bottom lift or layer of either inferior leather or a substitute for leather, said lift being shorter than the adjoining lift or layer and with its short end toward the breast or straight end of said heel, said bottom lift forming a heel seat, the bottom or concave surface thereof being skived to a bevel, whereby said heel seat and heel are adjustable relatively to said front portion and are adapted to be lapped and secured 75 together by the heel nailing substantially as described.

5. As a new article of manufacture, a heel for a shoe comprising a short sole of sole leather having its shank end beveled, 85 said heel having a heel seat portion secured thereto and forming a part thereof, said heel seat portion being adapted to form an extension of said short sole and having its inner end beveled to lap the beveled end of said 90 short sole.

Signed at Jefferson City, Missouri, this 23d day of August, 1913.

CHARLES TWEEDIE.
